United States Patent Office

Des. 218,382
Patented Aug. 18, 1970

218,382

PANTY GIRDLE

Olga Erteszek, Los Angeles, Calif., assignor to Olga
Company, Van Nuys, Calif., a corporation of California

Filed July 15, 1969, Ser. No. 18,203

Term of patent 14 years

Int. Cl. D2—02

U.S. Cl. D2—4

FIG. 1.

FIG. 2.

FIG. 1 is a front perspective view of a panty girdle, showing my new design; and

FIG. 2 is a rear perspective view thereof.

I claim:

The ornamental design for a panty girdle, substantially as shown.
